US00D660232S

(12) **United States Design Patent** (10) **Patent No.:** **US D660,232 S**
Elison et al. (45) **Date of Patent:** **** May 22, 2012**

(54) **BATTERY**(75) Inventors: **Nicholas E. Elison**, Milwaukee, WI (US); **Glenn W. Andersen**, Hartford, WI (US)(73) Assignee: **Johnson Controls Technology Company**, Holland, MI (US)(**) Term: **14 Years**(21) Appl. No.: **29/404,783**(22) Filed: **Oct. 25, 2011**(51) LOC (9) Cl. .... **13-02**(52) U.S. Cl. **D13/119**

(58) Field of Classification Search D13/102-106, D13/110, 118-119, 184; 429/96-100, 149, 429/163, 176, 187

See application file for complete search history.

(57) **CLAIM**

The ornamental design for a battery, as shown and described.

DESCRIPTION

FIG. 1 is a top isometric view of the battery according to an exemplary embodiment;

FIG. 2 is a first side elevation view thereof;

FIG. 3 is a first end elevation view thereof;

FIG. 4 is a second side elevation view thereof;

FIG. 5 is a second end elevation view thereof;

FIG. 6 is a top plan view thereof; and,

FIG. 7 is a bottom plan view thereof.

The broken lines shown in the figures are for illustrative purposes only, and form no part of the claimed design.
